UNITED STATES PATENT OFFICE.

THERON H. BLY, OF MINNEAPOLIS, MINNESOTA.

DESIGN FOR A SPECULUM MEMBER.

SPECIFICATION forming part of Design No. 31,278, dated July 25, 1899.

Application filed November 5, 1898. Serial No. 695,638. Term of patent 7 years.

To all whom it may concern:

Be it known that I, THERON H. BLY, residing in the city of Minneapolis, county of Hennepin, State of Minnesota, have invented and produced a new and original Design for a Speculum Member, of which the following is a specification, reference being had to the accompanying drawing, forming a part thereof.

The single view shows in perspective one member of a speculum designed in accordance with my invention.

By reference to the drawing it will be seen that the blade-like portion or spreader 1 and handle portion 2 are offset on approximately parallel lines. The blade 1 and handle 2 are connected by an intermediate section 3, which is curved first in the plane of said handle 2 and then is again curved approximately in

the plane of the blade 1. That end of the blade 1 which joins the section 3 is of semi-bell-mouthing form, as shown at 4, and this flange 4 is curved at its lower extremity and blended into the curved section 3. At the intermediate portion of the compound-curved section 3 is a pair of laterally-spaced projections 5.

Having described my invention, what I claim, and desire to secure by Letters Patent of the United States, is—

The design for a speculum member, substantially as herein shown and described.

THERON H. BLY.

In presence of—

JAS. F. WILLIAMSON,
F. D. MERCHANT.
